FIG. 17.

UNITED STATES PATENT OFFICE.

SOREN CHRISTIAN REPSHOLDT, OF OMAHA, NEBRASKA.

TRAFFIC-SIGNAL TOWER.

1,360,796.

Specification of Letters Patent. Patented Nov. 30, 1920.

Application filed July 15, 1919. Serial No. 311,111.

To all whom it may concern:

Be it known that I, SOREN CHRISTIAN REPSHOLDT, a citizen of the United States of America, residing at Omaha, in the county of Douglas and State of Nebraska, have invented certain new and useful Improvements in Traffic-Signal Towers, of which the following is a specification.

This invention relates to certain new and useful improvements in traffic signal towers.

The primary object of the invention is the provision of a signal tower especially adapted for street crossings provided with traffic signals readily operable by the crossing officer, provision being made for the display of orders at opposite sides of the tower viewable in the directions of the oncoming traffic.

A further object of the device is the provision of an elevated tower at street intersections for the accommodation of the traffic or crossing officer stationed thereat, an efficient means being arranged whereby the officer may gain exit and entrance to the tower while the latter is provided with telephonic communication with distantly positioned similar towers at other street corners.

A still further object of the invention is the provision of a plurality of suitably arranged crossing signals having illuminating devices, opposite ones of the signals being readily shiftable simultaneously by the officer in charge in accordance with the traffic regulations, readily discernible audible alarms being automatically sounded for denoting which of the two through courses at the street intersections is open for traffic.

In the drawings forming part of this application and in which like reference characters refer to corresponding parts throughout the several views,

Figure 1 is a perspective view of the invention illustrating the same in use at a street crossing and also showing diagrammatically an operating station located at a distance from the tower,

Fig. 2 is an enlarged vertical transverse sectional view thereof,

Fig. 3 is a horizontal transverse sectional view taken substantially upon line III-III of Fig. 2,

Fig. 4 is a sectional view similar to Fig. 3 with two of the signal arms elevated,

Fig. 5 is a transverse sectional view taken substantially upon line V-V of Fig. 2,

Fig. 6 is a transverse sectional view taken upon line VI-VI of Fig. 2,

Fig. 7 is an elevational view of the signal drum employed in the invention,

Fig. 8 is a transverse sectional view of the upper portion of the device taken upon a plane perpendicular to the line of section of Fig. 2 and showing the alarm mechanism,

Figs. 9 and 10 are perspective views of portions of the alarm mechanism,

Fig. 11 is a detail view showing a different manner of displaying color signals,

Fig. 12 is a view of a modification of the device broken away and partly in vertical section,

Fig. 13 is a horizontal sectional view of the device shown in Fig. 12 partly broken away,

Fig. 14 is a fragmentary enlarged detail view illustrating the means for retaining the signal arms in operative position.

Fig. 15 is a horizontal sectional view of the device shown in Fig. 14,

Fig. 16 is a view in perspective, partly broken away, and illustrating details of the device shown in Fig. 12,

Fig. 17 is a view similar to Fig. 12 viewing the device at right angles to said Fig. 12, and

Fig. 18 is a horizontal sectional view of the device shown in Fig. 17.

My invention broadly consists of a tower 10, octagonal in horizontal cross section, mounted upon the top of a tubular column or post 11 vertically positioned at a street crossing, which may be provided as herein illustrated with separate car lines 12 and 13 crossing each other perpendicularly. The tracks 12 are represented in Fig. 1 of the drawings as the north and south tracks while the tracks 13 represent the east and west tracks, it being understood that the traffic upon said tracks as well as the streets upon which they are positioned travels forwardly upon the right hand side of the street in the customary manner and my invention is defined for signaling both visually and audibly in the night as well as the daytime for notifying the approach of vehicles upon both of the intersecting streets as to which crossing is clear and which one is closed at the time of giving the signal.

The tower 10 has a floor 14 for supporting an occupant located above the bottom 15 of the tower, providing a chamber 16 between

said floor and bottom. The inclosed portion 17 of the tower is connected to the roof or dome 18 by four posts 19 providing window openings 20 between the posts. Signaling 5 semaphore arms 21 are swingingly mounted through vertical slots 22 in the post 20 hinged to inwardly projecting brackets or bearings 23 carried by the posts. The arms 21 are normally depressed substantially in- 10 closed within the tower 10 engaging straps or stop members 24 inwardly of the tower, said arms having a suitable word such as "Stop" as at 25 provided upon its opposite sides.

15 A hollow shaft 26 is journaled through the column 11 and floor 14, being provided with an operating handle 27 within the tower 10 for turning the shaft. The traffic or police officer within the tower 10 may readily operate the opposite pairs of arms 21 by means 20 of the handle 27 through the agency of a cam disk 28 carried by the shaft 26 and having oppositely positioned double cam or flange portions 29 operatively engaging the 25 upper end of the arms 21.

The cams 29 are positioned between adjacent arms 21 and out of contact therewith when the device is at rest with all of the arms 21 in their substantially vertical and 30 inoperative positions. The cams 29 are bent inwardly as indicated in Fig. 3 of the drawings and upon turning the disk 28, engage the outer edges of the upper end portions 35 of the arms 21 as at 30, swinging the arms outwardly, while the cams 29, being also curved downwardly, further exert a downward pressure upon the arm portions 30 during the further rotation of the disk 28, whereby the opposite arms 21 are moved to 40 their outstretched slightly upwardly inclined position as shown in Figs. 1 and 4 of the drawings. Upon a reverse rotation of the disk 28, the cams 29 are released from the arms 21, which, by reason of their own 45 weight, return to their normally inoperative lowered position as shown in Figs. 2 and 3 of the drawings. It will be obvious that a continuance of the reverse turning of the disk 28 by the handle 27 brings the cams 29 into operative engagement with the other 50 pair of opposite arms 21 for presenting signals to the other street of the intersection or crossing. In some cities, where streets are 55 extremely narrow and congested, it is desirable to operate the signal arms from the sidewalk, and in order to place this invention in use at such points, it is only necessary to provide an underground operative connection 31 between the shaft 26 and the 60 handle 32 secured upon the vertical shaft 33 suitably mounted within the inclosure 34 situated upon the sidewalk 35. As such connections are extremely common in railway signals and as the particular forms of 65 these connections do not form a part of the

present invention, the same have merely been indicated in a diagrammatic manner.

A door 31 in the column 11 permits the attachment of a removable handle 32 to the shaft 26 so that an officer stationed upon the 70 roadway beneath the tower 10 may readily operate the signal arms 21 in the manner heretofore noted. A telephone 33 is positioned within the tower 10 for the use of the officer in charge of the signal for communicating with a distant point such as another signal tower for giving notice to intercept a vehicle exceeding the speed limit, line wires 34 being provided for the telephone 33 and passing through the shaft 26. A reflecting hood 35 is carried by the dome 18 adjacent each of the arms 21, having an electric lamp 36 therein for illuminating the signal arms in the night time, the line wires 37 of the lamps 36 being also carried through 85 the shaft 26. A drum 38 in the form of a split ring is mounted for rotation in the chamber 16 and clamped for turning with the shaft 26 by means of inwardly projecting radial arms 39 as best indicated in Fig. 90 6 of the drawings. Casters 40 upon the bottom of the drum 38 are mounted for traveling upon the bottom 15 of the tower. Alternate red and green panels 41 and 42, eight in 95 number, are provided in the drum 38, so arranged that whenever a pair of arms 21 is elevated, two of the green panels 42 will be visible therebeneath through the windows 43 provided in the tower sides 17 at points beneath each of the slots 22. When the pair 100 of stop arms 21 is operatively positioned, red panels 41 will be visible through the windows 43 beneath the depressed arms 21 and the word "Stop" being provided upon the red panels, the vehicles approaching the 105 tower 10 in opposite directions upon one of the intersecting streets such as the east and west illustrated in Fig. 1, will be met by the word "Stop," visible at the three places, that is, from the nearest window 43 and upon the 110 lateral outstretched signal arms 21. The vehicles approaching the tower upon the north and south street will at such times be met with only the green panels 42 showing through the windows 43 and in noting that 115 the line of traffic is open for travel north and south.

Electric lamps 44 are mounted upon the bottom 15 within the chamber 16 for lighting whenever desired so as to illuminate the 120 panels 41 and 42, it being understood that the lamps 44 may also be inserted with the wires 37 and controlled by a suitable switch, unnecessary to herein illustrate.

An alarm bell 45 is mounted within the 125 dome 18 upon an arch 46 adapted for striking a single impulse when the east and west line of traffic is open for traffic and striking two impulses when the signal is changed for opening the north and south bound traffic. 130

An arm 48 upon the upper end of the shaft 26 for turning therewith has an upstanding lug 49 adapted to hit a pivoted trip 50 upon the arch 46 upon turning the arm 48 in either direction, thereby elevating the clapper 47 against the bell 45 for ringing the latter. A pivoted lug 51 upon the arm 48 adjacent the lug 49 is also engaged by the trip 50 when the shaft 26 is turned for presenting the proper arm 21 to open the north and south bound traffic. The return movement of the shaft 26, however, brings the trip 50 into wiping contact with the lug 51 for ratcheting thereover so that the trip is only actuated by the lug 49, thereby imparting a single actuation to the clapper 47 and ringing the bell 45 once to indicate that the east and west line is open for traffic. In this manner, the operation of the signal arms 21 by any one of the handles 27, 32, or 32' automatically sounds the alarm bell 45 to audibly indicate which course of travel is open as well as to simultaneously present a visual indication of the traffic conditions at four sides of the tower through the windows 43. A protecting plate 52 is preferably provided overlying the bell 45 and the circular central opening 53 in the top of the dome 18.

The trap door 54 in the tower bottom 15 is connected by a link 55 with a similar door 56 in the floor 14 whereby said trap doors are connected for simultaneous operation. A ladder 57 is hinged to the bottom 15 as at 58 by the upper angular extension 59 of the latter while a cord 60 connects the ladder 57 with the door 54 and passes over a pulley 61 in the chamber 16. When the doors 54 and 56 are closed and the officer desires to enter the tower 10, he mounts the ladder 57 which 40 pulls downwardly upon the cord 61 and opens the doors 54 and 56. After passing upwardly into the tower, the closing of the upper door 56 swings the lower door 54 to its closed position. In leaving the tower, 45 the upper door 56 is opened by means of its handle 62 which opens the lower door 54 and the officer descends to the street by means of the ladder 57. By pulling upon a cord 63 attached to the door 54, both of the doors 50 54 and 56 are closed. A fire bell or gong 64 may be provided upon the tower bottom 15 if desired, and it will be seen that a serviceable traffic adjunct is provided whereby accidental collisions may be avoided at street 55 intersections, audible signals as well as signs visible by day and by night, being positive in their operation under the manipulation of the officer in charge, either within the tower 10 or outside of the same.

60 In Fig. 11, I have illustrated a swinging signal arm 21' carried by the casing 65 with an annular screen 66 connected thereto by links 67 for vertical movement. Electric lamp 68 within the casing 65 is in a position 65 to throw light upon a red panel 69 in the

screen 66 when the arm 21' is elevated as a stop signal but throws light upon a green panel 70 of the screen when the arm 21' is lowered and the screen is in its normal elevated position.

70 Referring to Figs. 12 to 18, inclusive, wherein a further modification of the invention is shown, the signal arms 21' are pivotally mounted as at 23' within the tower 10 so as to swing upwardly within the latter 75 through the slots 22' to an inoperative position. In order to elevate the signal arms, the latter are pulled upwardly by the rods 71 which are pivotally attached as at 72 at their lower ends to the signal arms and are guided 80 for vertical movement by the brackets 73 fastened inside of the tower 10 adjacent the top thereof. The upper ends of the rods 71 are directed inwardly as at 74 and provided with a suitable anti-friction roller 75 85 bearing upon the upper face of the cam disk 76 which is rigidly fastened to and turns with the operating shaft 26' adapted to be turned by means of the handle 27' or the like. It will be obvious that when the disk 90 76 is turned so as to cause its cams 77 to ride under the opposite friction rollers 75, the rods 71 will be pulled upwardly and thereby swing the signal arms 21' to the position shown in Fig. 12 from the position shown in 95 Fig. 17.

100 The rods 71 are apertured for reception of a locking pin 78 which also passes through the bracket 73 for maintaining the signal arms in their raised inoperative position when the device is not in use. A spring 79 or other cushion means is provided within the tower 10 to be struck by the signal arms 21' so as to cushion the same when coming to rest in their inoperative positions. The 105 rods 71 are bifurcated to provide a pair of legs 80 between which the signal arms are positioned when in their inoperative positions, and springs 81 are also provided to hold the bars 71 inwardly with the pins 78 110 disposed in the apertures thereof. In this form of the invention, the screens 66 are directly pivotally attached to the stop arms 21' and the red panel 69 is disposed in the lower portion of each screen instead of in 115 the upper portion thereof as in the form of Fig. 11 so that the stop signal will be properly displayed with respect to the signal arms at opposite sides of the tower.

120 From the foregoing description, it is believed that the construction and operation of the various forms of the invention herein shown and described will be readily understood by those skilled in the art.

125 While the preferable embodiments of my invention are herein set forth, it will nevertheless be understood that minor changes may be made therein without departing from the spirit and scope of the invention as claimed.

What I claim as new is:—

1. A traffic signal including a tower adapted to be mounted at the intersection of a pair of streets, four equally spaced signal arms pivoted to the tower so as to swing radially outwardly therefrom and having the word "Stop" upon the opposite faces thereof, said tower being provided with slots whereby said signal arms may swing there-through to an unexposed position within the tower when substantially vertically disposed, and means including a cam disk simultaneously operable for causing the signals to assume positions wherein opposite ones of the same are in outwardly swung operative position and the remainder are in inwardly swung unexposed position.
2. A traffic signal including a tower adapted to be mounted at the intersection of a pair of streets, four equally spaced signal arms pivoted to the tower so as to swing radially outwardly therefrom and having the word "Stop" upon the opposite faces thereof, said tower being provided with slots whereby said signal arms may swing there-through to an unexposed position within the tower when substantially vertically disposed, means including a cam disk simultaneously operable for causing the signals to assume positions wherein opposite ones of the same are in outwardly swung operative position and the remainder are in inwardly swung unexposed position, lamps within the tower, transparent signs within the tower including panels with the words "Cross" and "Stop" thereon and arranged so that the light from said lamps may pass therethrough, and means to simultaneously operate said panels and said signal arms whereby the word "Cross" is displayed from opposite panels positioned beneath the operative signal arms when the word "Stop" is simultaneously displayed beneath the inoperative signal arms.
3. A traffic signal for intersecting roadways comprising a tower, indicating elements at the sides of the tower pivoted to be swung outwardly for facing the roadways, operating means for selectively engaging opposite pairs of the indicating elements, and actuating means for the operating means positioned within the tower, said tower having side openings beneath the indicating elements, and an indicating drum upon the actuating means adapted for presenting stop signals at the side openings positioned beneath the inoperative pair of indicating elements.
4. A traffic signal for intersecting roadways comprising a support, indicating elements at the sides of the support adapted to be swung outwardly to exposed position, an actuating shaft within the tower, an operating cam disk upon the shaft having two double cam portions arranged to selectively outwardly swing the indicating elements upon turning of said shaft, an indicating drum carried by the shaft and having "Stop" and "Cross" signal panels for visual display at opposite sides of the tower respectively adjacent the inoperative and operative indicating elements.
5. A traffic signal for intersecting roadways comprising an elevated casing or tower, signal arms pivoted to the sides of the tower for swinging movement outwardly therefrom to exposed position, a shaft axially journaled through the tower, means within the tower for turning said shaft from within the tower, removable means outside of the tower and adjacent the ground, for turning said shaft and a disk upon the shaft adjacent the top of the tower having double cams operatively associated with the arms for selectively outwardly swinging the separate pairs of opposite arms at will.

In testimony whereof I affix my signature.
SOREN CHRISTIAN REPSHOLDT.
